UNITED STATES PATENT OFFICE.

PETER C. SIMMONS, OF FOREST LAKE, MINNESOTA.

BURIAL-CASKET.

1,072,182.

Specification of Letters Patent.

Patented Sept. 2, 1913.

Application filed December 23, 1912. Serial No. 738,397.

To all whom it may concern:

Be it known that I, PETER C. SIMMONS, citizen of the United States, residing at Forest Lake, in the county of Washington 5 and State of Minnesota, have invented certain new and useful Improvements in Burial-Caskets, of which the following is a specification.

My invention relates to improvements in 10 burial caskets, and its object is to provide means whereby a body laid in the casket may be as near a natural position of repose as possible. I attain this object by the mechanism illustrated in the accompanying 15 drawing, in which—

Figure 1 is a vertical, longitudinal section of a casket showing my adjusting device in place with the actuating roller placed well up in the head of the casket. Fig. 2 is a 20 plan of the casket with the cover removed to show the relative positions of the several elements that go to make up my invention. Fig. 3 is a longitudinal section, as in Fig. 1, with the actuating roller near the bottom of 25 the casket. Fig. 4 is a detached view of the actuating screw gear and a short handled crank for use in manipulating the same when used as in Figs. 1 and 3, and Fig. 5 is a modified crank for use from the top of the 30 casket in Fig. 3.

Similar letters refer to similar parts throughout the several views.

In the accompanying drawing A represents an ordinary burial casket with the 35 cover removed.

B represents a flexible auxiliary bottom to the casket that is secured to the fixed bottom, as at B'', at one end, and the other end is secured to a laterally disposed shaft C at the 40 head end of the casket. This shaft may be placed well up toward the top of the casket, as in Fig. 1, or well down toward the bottom of the casket, as in Fig. 3, and should be supported upon standards c c, so as not 45 to pass into, or interfere with the sides of the casket. The shaft C has one member, as C', of a screw gear mounted upon it, and the other member, D, of the screw gear is mounted at the head of the casket upon proper 50 supporting arms, as D', in position to

properly mesh with the member C'. This member of the screw gear has bearings d d that are designed to engage the arms D' to hold the gear in proper position to actuate the gear C', and at the ends 55 squares, as d', or other suitable construction, are formed for the reception of the cranks E or E', as the case may be, by means of which the member D is made to revolve for the purpose of revolving the shaft C to wind 60 up, or to unwind the flexible bottom on the roller C, for the purpose of adjusting the body to the desired position. When the shaft C is placed high up in the casket, as in Fig. 1, and it is desired to operate the 65 screw gears from above, or if the shaft is placed low down in the casket and it is desired to operate the gears from below, as indicated in Fig. 3, the short crank E may be used to the best advantage, but if it is desired 70 to operate the gears from below in Fig. 1, or from above in Fig. 3 it will be necessary to use the long handled crank E', shown in Fig. 5.

The slot A' in the flexible bottom is necessary to allow the bottom B to be wound around the shaft C without danger of becoming clogged in the screw gear and obstructing the operation of the device. 75

What is claimed as new, and desired to be 80 secured by Letters Patent of the United States, is:

1. In combination with a burial casket, a flexible auxiliary bottom secured at one end to the bottom of the casket, and at the other 85 end to a revoluble roller, and means for actuating said roller to properly adjust the auxiliary bottom.

2. In combination with a burial casket, a flexible auxiliary bottom secured at one end 90 to the bottom of the casket, a revoluble roller secured to the other end of the auxiliary bottom, a worm gear for actuating said roller for adjusting the auxiliary bottom.

Signed at Forest Lake, Minnesota, De- 95 cember 9th, 1912.

PETER C. SIMMONS.
